[57] CLAIM

The ornamental design for a combined support for holding and displaying cards, substantially as shown and described.

DESCRIPTION

FIG. 1 is a top plan view of a combined support for holding and displaying cards showing my new design; FIG. 2 is a front elevational view thereof.

FIG. 3 is a rear elevational view thereof.

FIG. 4 is a right side elevational view thereof, the left side being a mirror image.

FIG. 5 is a bottom plan view thereof.

FIG. 6 is a top plan view of a second embodiment of the design of FIG. 1;

FIG. 7 is a front elevational view of FIG. 6;

FIG. 8 is a rear elevational view of FIG. 6;

FIG. 9 is a right side elevational view of FIG. 6;

FIG. 10 is a left side elevational view of FIG. 6;

FIG. 11 is a bottom plan view of FIG. 6.
